(57) **CLAIM**

The ornamental design for a nail polish bottle, as shown and described.

DESCRIPTION

FIG. 1 is a perspective view of a nail polish bottle showing my new design.

FIG. 2 is a front view of a nail polish bottle.

FIG. 3 is a rear view of a nail polish bottle.

FIG. 4 is a left side view of a nail polish bottle.

FIG. 5 is a right side view of a nail polish bottle.

FIG. 6 is a top view of a nail polish bottle; and,

FIG. 7 is a bottom view of a nail polish bottle.

The broken lines, the areas within them, the unshaded areas bounded by both broken and solid lines depict portions of the nail polish bottle that form no part of the claimed design.
